UNITED STATES PATENT OFFICE.

EMIL M. KRAMER, OF PAXTON, ILLINOIS.

INTERNAL-COMBUSTION-ENGINE EQUIPMENT.

1,164,199.

Specification of Letters Patent. Patented Dec. 14, 1915.

Application filed June 7, 1915. Serial No. 32,551.

To all whom it may concern:

Be it known that I, EMIL M. KRAMER, a citizen of the United States, residing at Paxton, in the county of Ford and State of Illinois, have invented a new and useful Internal-Combustion-Engine Equipment, of which the following is a specification.

My invention relates to improvement in equipment for internal combustion engines, providing for causing the explosive charges introduced into the engine for firing therein, to contain a desirable amount of water-vapor, thereby to produce highly efficient and economical operation of the engine; and my object is to provide a novel and simple apparatus of this character, which may be used under widely differing conditions presented by engine structures of different types.

Referring to the accompanying drawing: Figure 1 is a view in elevation, partly diagrammatic, of an internal combustion engine, with a carbureter therefor as commonly used on automobiles, and means, constructed in accordance with my invention, for supplying damp air to the carbureter; Fig. 2 is an enlarged section taken at the line 2 on Fig. 1 and viewed in the direction of the arrow; and Fig. 3, a section taken at the line 3 on Fig. 1 and viewed in the direction of the arrow.

In Fig. 1, I have shown my invention as applied to internal combustion engine equipment as used on automobiles, in which 4 is the engine, 5 the inlet-pipe for conducting explosive charges from the carbureter 6 into the cylinders of the engine, and 7, the exhaust pipe. The carbureter shown may be of any suitable construction as commonly used. In the drawings, the gasolene-inlet for the carbureter is represented at 8, and the air-inlet at 10, the carbureter shown having a single air-inlet, though the invention may be used with a plural air-inlet carbureter. The air-inlet 10 opens into a pipe 11 which communicates with the lower end of a pipe 12 extending at its upper end into a tank 13 for water, provided with a capped water-filling opening 13a. The tank 13 also contains a pipe 14 which extends at its upper end into said tank, and at its lower, open, end through the bottom of the tank, this pipe being provided for conducting air into the tank above the water level 15 therein. The tank 13 is provided for mixing water-vapor with the air supplied to it through the pipe

14, by the suction action of the engine, the water in the tank 13 being heated in any desirable way. In the construction illustrated, I avail myself of the waste-heat generated by the engine, for heating the water in the tank, and this is accomplished in the preferred way, by providing a coil 16 of pipe about the exhaust-pipe 7 of the engine and connecting the ends of this coil with the interior of the tank 13 in any way suitable to obtain a circulation of the water therein, this being effected in the construction illustrated by attaching one end of the coil 16 at a higher point on the tank than the other. The heat from the exhaust-pipe causes the water in the tank 13 to become vaporized, the vapor mixing with the air supplied to the tank through the pipe 14 and thus charging it with moisture before entering the carbureter. By preference the air before entering the tank 13 by way of the pipe 14 is heated, and as a convenient way of doing this, I utilize the heat from the exhaust gases, preferably employing a funnel-shaped inlet 17 for the pipe 14 which lies closely adjacent to the exhaust pipe in partially overlapping relation, but out of contact therewith, as shown. The tank 13 preferably is provided with means for preventing the water therein from splashing into the upper open ends of the pipes 12 and 14, the form of means shown comprising radially disposed plates 18 confined in the tank 13 in accordance with common practice.

It will readily be understood from the foregoing that water-vapor in approximately uniform quantities is mixed with the air and gasolene to form the charges to be fired in the cylinders of the engine, and that by my invention the advantages resulting from the mixture of water-vapor with the air and gasolene, or the like, may be availed of.

While I have illustrated and described a certain arrangement of parts for carrying out my invention, I do not wish to be understood as intending to limit it thereto, as various modifications and alterations may be made therein without departing from the spirit of my invention.

What I claim as new and desire to secure by Letters Patent is:

1. The combination with an internal combustion engine, of a tank for water containing an air inlet, a pipe-coil arranged to be

heated by the exhaust pipe of the engine and connected at its ends with said tank, a conduit opening into said tank above the water therein, and in communication with the cylinders of the engine, and means for mixing gasoline, or the like, with the air and vapor passing through said conduit.

2. The combination with an internal combustion engine, of a tank for water containing an air inlet, a pipe-coil arranged to be heated by the exhaust pipe of the engine and connected at its ends at different elevations with said tank, a conduit opening into said tank above the water therein and in communication with the cylinders of the engine, and means for mixing gasoline, or the like, with the air and vapor passing through said conduit.

3. The combination with an internal com-

bustion engine, of a tank for water, means 20 for heating the water in said tank, pipes extending upwardly through said tank with their upper ends above the water-level therein, one of said pipes at its other end being in communication with the carburetor of the 25 engine and the other of said pipes at its other end in communication with the atmosphere and arranged to cause air passing therethrough to be heated by the exhaust from the engine, and means for mixing gasoline, or the like, with the air and vapor passing through said pipe.

In testimony whereof I have hereunto set my hand this 21st day of May, A. D. 1915.

EMIL M. KRAMER.
